UNITED STATES PATENT OFFICE.

ROBERT DAVIS, OF BROOKLYN, NEW YORK, ASSIGNOR TO BROOKLYN BOX TOE COMPANY, OF BROOKLYN, NEW YORK, A CORPORATION OF NEW YORK.

SHANK STIFFENER.

Application filed December 22, 1924. Serial No. 757,356.

To all whom it may concern:

Be it known that I, ROBERT DAVIS, a citizen of the United States, residing at Brooklyn, in the county of Kings and State of New York, have invented new and useful Improvements in Shank Stiffeners, of which the following is a specification.

This invention relates to arch supporters for shoes of that type in which a leather member provided with a spring stiffener is arranged between the inner and outer sole to prevent collapse of the arch.

The object of the present invention is to provide the member with a cut-out portion at its forward end so that it will lie flat at the arch curve which joins that portion of the sole where the ball of the foot is supported.

Heretofore, in arch supporters of the kind described the forward part of the member had a tendency to bulge or wrinkle especially when the glue or cement by which it was fastened to the sole became loosened by moisture permeating between the soles. It is the object of the invention to so shape the front portion of the member that it will provide sufficient surface for cementing to the sole, and at the same time eliminate as much material as possible which may cause the inner sole to swell or form a ridge above the forward edge of the member.

The novel features of the invention are more fully described in the following specification and claims, and illustrated in the accompanying drawing in which:—

Fig. 1 represents a sectional side elevation of a shoe embodying this invention.

Fig. 2 is a perspective view of the arch supporting member.

In the drawing is shown an arch supporting member consisting of a heel portion 5 and a forward cut-out portion 6 forming bifurcated ends 7. The member is usually cemented between an inner sole 8 and an outer sole 9 of a shoe. The member is provided with a metal shank 10 so as to stiffen it and at the same time give it resiliency

to prevent breakdown of the arch part of the shoe.

As indicated in Fig. 1 the bifurcated portion of the member is located under the ball of the foot and by reason of the cut-out or opening it substantially eliminates the straight-forward edge where the pressure of the foot is the greatest.

When the foot is in motion the heel portion of the shoe is raised upward as shown in dotted lines and the sole of the shoe adjacent the metatarso-phalangeal joint will flex thus bending that portion of the stiffener positioned in a line with the joint. By having the edges nicked or notched as shown at 11 it substantially forms a transverse line of demarcation to permit greater ease of flexure at these points and wrinkling of the stiffener especially near its border when it is bent will be eliminated. The notches also prevent gathering of the material at the side edges caused by flexion at a predetermined point. By having the line of flexure near its forward end it relieves the strain over the entire stiffener preventing breakage of the steel shank and the inherent resiliency of the leather or other material will cause it to fly back after the force is removed.

I claim:—

1. A shank stiffener for shoes comprising a resilient leather member adapted to be positioned between the inner and outer soles, and notches located one opposite the other in the forward edges of the member to permit greater ease of transverse flexure adjacent the metatarso-phalangeal joint.

2. A shank stiffener for shoes comprising a resilient leather member adapted to be positioned between the inner and outer soles provided with forwardly cut out end, and notches located in the forward edges of the member to permit greater ease of transverse flexure adjacent the metatarso-phalangeal joint.

In testimony whereof I have hereunto set my hand.

ROBERT DAVIS.
